CLAIM

The ornamental design for a holder used for a cutting tool, as shown and described.

DESCRIPTION

FIG. 1 is a front view of a holder used for a cutting tool, showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a perspective view 1 thereof;

FIG. 8 is a perspective view 2 thereof;

FIG. 9 is an enlarged view of IX-IX portion of FIG. 1;

FIG. 10 is a cross sectional view taken along line X-X of FIG. 3;

FIG. 11 is an enlarged view of XI-XI portion of FIG. 4;

FIG. 12 is an enlarged left side view thereof;

FIG. 13 is an enlarged perspective view of XIII-XIII portion of FIG. 7;

FIG. 14 is an enlarged perspective view of XIV-XIV portion of FIG. 8;

FIG. 15 is a cross sectional view taken along line XV-XV of FIG. 9;

FIG. 16 is a cross sectional view taken along line XVI-XVI of FIG. 9;

FIG. 17 is a referential enlarged view 1 of IX-IX portion of FIG. 1;

(Continued)

FIG. 18 is a referential enlarged view 2 of XI-XI portion of FIG. 4; and, FIG. 19 is a referential enlarged left side view thereof. The two-dot chain lines in the referential enlarged views 1 and 2 and the referential enlarged left side view illustrate flow paths that are provided inside the cutting tool holder.
